AUTOMATIC SAMPLING APPARATUS

Vincent C. Lorenz, Anaconda, Mont., assignor of
one-fourth to Charles W. Morse, Anaconda,
Mont.

Application November 22, 1943, Serial No. 511,334

12 Claims. (Cl. 73—423)

1

The present invention relates to improvements in automatic sampling apparatus, and more particularly to the driving mechanism of the same.

An object of the invention is to provide a type of driving mechanism which is adapted to intermittent operation and is susceptible to adjustment in order to operate at the desired intervals.

Another object of the invention is to provide a driving mechanism of a simple and reliable form; not dependent on electrical timing or actuating devices; and requiring a minimum of service or maintenance to keep it in satisfactory operating condition.

A further object of the invention is to provide an improved driving mechanism incorporating a device that will require the mechanism to make a complete revolution.

A further object of the invention is to provide an improved driving mechanism so constructed and arranged as to cause the sampling device to cut rapidly through the entire stream, in fact so rapidly that the objectionable riffle cutter usually employed in the launder to reduce the volume of the stream to be sampled may be done away with.

A still further object of the invention is to provide a stop mechanism for the driving mechanism which will damp the oscillations of the mechanism after the same has completed a full stroke, and which will bring the driving mechanism rapidly to rest in a position of unstable equilibrium in readiness for the next successive sample taking.

With the foregoing and other objects in view the invention will be more fully described hereinafter and will be more fully pointed out in the appended claims.

In the drawings in which like or corresponding reference characters denote the same or similar parts throughout the several views,

Figure 1 is a side elevation, with parts broken away, showing an improved automatic sampling equipment and driving mechanism constructed in accordance with the present invention.

Figure 2 is an end view of the same, with parts broken away and parts shown in section.

Figure 3 is a perspective view of the improved bucket employed.

Figure 4 is a fragmentary side view of the improved stop or check device showing the same in full and dotted line positions.

Figure 5 is a vertical section taken on the line 5—5 in Figure 4.

Figure 6 is a fragmentary perspective view

2 showing the arcuate base support and hook and trigger device.

Figure 7 is a fragmentary vertical section taken on an enlarged scale through the base or trough support and through the hook and trigger and associated devices.

Figure 8 is a fragmentary side view with parts broken away and parts shown in section of the sample receiver and its support, and

Figure 9 is a vertical section taken on the line 9—9 in Figure 8.

Referring more particularly to the drawings 10 designates a bucket, partially covered by a hood 11 and mounted rigidly on an arm 12. Such arm forms a part of, or is rigidly attached to, a shaft 13 journaled in bearings 14 carried upon an appropriate support or portion of the framework of the sampling equipment.

The bucket is continuously fed with water from 20 a nozzle 15 supplied, under constant head, from a supply tank (not shown) or other suitable source.

Affixed to the shaft 13 is a rod 16 carrying a weight 17 fixed on the rod. The rod 16 or the 25 weight 17 carries a foot or shoe 18 which is preferably frusto-conical in form. The rod 16 or shoe 18 is adapted to rest against the free end of a flexible flat spring 19 carried by a suitable part of the apparatus and biased to an upwardly curled position (Figure 1 and Figure 4) which invades the circle of movement traversed by the shoe 18, for which see the dotted position of Figure 4.

As best seen in Figure 7, a stop 20 is pivoted at 21 in a supporting block 22 and is equipped with 35 a hook 23 at one end and a trigger 24 at its other end. The block 22 has lugs 25 embracing the sides of the head 26 of a rod 27. The head and lugs are pivoted together on the pivot pin 28. The rod 27 carries a collar 29 normally abutting 40 against a stop wall 30 which also serves as a bearing through which the rod 27 may reciprocate. The stop wall 30 also subserves a third function as an abutment wall against which one end of a coil spring 31 engages. The other end 45 of this coil spring (Figure 1) abuts against a flange 32 of an adjusting nut 33 which may be threaded upon the right end of the rod 27. The coil spring 31 is wound in a suitable number of convolutions or helices about the rod 27 between the stop wall 30 and the nut 33. The axial thrust of the spring 31 against nut 33 biases rod 27 to a right hand position in which the stop collar 29 abuts the wall 30.

Wall 30 may be a part of a housing 34 which encloses a portion of the spring 31, which supports

the flat flexible spring 19 and which provides an extension or base support 35 (Figures 6 and 7) of a trough shape in cross section and of arcuate form in which to slidably and adjustably support the supporting block 22. In the base of this arcuate trough 35 is a slit 36 through which projects the shank 37 of a screw threaded in a threaded socket 38 of the base of the supporting block 22. The head 39 of the screw is wider than the slot 36 and slides along the bottom surface of the trough or base 35 to hold the block 22 in the trough.

The shank of the screw passes freely through the slot 36 and is preferably unthreaded at this portion so as to slide smoothly back and forth in the slot. The screw shank and head constitute guides for the block 22 and also a holding or detent means to restrain the block in the trough but permit the block to have free reciprocating movement.

By reference to Figure 1, attention is called to the fact that the flat flexible spring 19 and the stop device 20 are so relatively arranged with respect to rod 16 and its shoe or foot 18 that the arm 16 and weight 17, when at rest, will assume a position which is angularly offset from the vertical in a clockwise direction, which is the direction of rotation of the combined bucket 10 and counterbalancing weight 17 about shaft 13.

A waste water trough 40, drained by outlet 41, is placed to receive water dumped by the bucket 10 during its rotary travel. The shaft 13 has affixed thereon a bevel pinion 42 (Figure 2) disposed in mesh with a companion bevel pinion 43 on a vertical shaft 44. The vertical shaft is supported by bearings 45 and 46. Near its lower end this shaft 44 carries a wedge-shaped cutter 47 (Figures 8 and 9) having a narrow open slot 48 in its upper edge, the walls of the cutter 47 diverging downwardly from such narrow slot 48, as seen in Figure 9. As seen in Figure 8, the base wall of the cutter 47 is diagonally disposed downwardly to an opening 49 by which the lowermost portion of the cutter 47 communicates with the interior of a hollow section 44^a of the shaft 44. This hollow section 44^a extends down into a covered bucket 50. The hollow shaft section 44^a extends down at one side of launder 51 (Figure 1). The bucket 50 is disposed at one side and below the launder 51 as indicated by the broken away portions of the parts in Figures 1 and 2.

Launder 52 (Figure 2) spills its pulp into the launder 51. The shaft 44 and cutter are so located that the cutter may be rotated into the pulp stream.

The operation is as follows:

Water from the nozzle 15, regulated to give the desired frequency of operation, slowly fills bucket 10 until the combined weight of the bucket 10 and its contents is sufficient to overcome the inertia of the offset weight 17 and its rod or supporting arm 16. The bucket 10 thereupon swings down in a clockwise direction, as viewed in Figure 1, lifting the weight 17. The shaft 13 is consequently rotated, bringing bucket 10 to a bottom position where it dumps its water into the trough 40. The hood 11 prevents the water in the bucket from being spilled in the early part of the revolution. When the bucket 10 is in its lowest position the diametrically offset weight 17 has passed the vertical center line and its mass continues the revolution bringing the empty bucket 10 back to its original upper position of Figure 1. If no checks were provided, the shaft 13 would make several revolutions and oscillations

before it finally came to rest. A reliable stop is thus essential.

As weight 17 is traveling its circular path of movement and when it approaches from the right its initial position (Figure 1), the foot or shoe 18, traveling along the lower arc of the circle, wipes across the upper face of the curved flat spring 19, depressing the free end of this spring, which is followed by the pressing down of the trigger 24 and the elevation of the hook 23 into the path of circular movement of the foot 18. When the foot 18 strikes the hook 23 the momentum of the weight 17 and entrained parts carries the hook 23 and the supporting block 22 to the left for a distance dependent upon the strength of the coil spring 31. The length of screw shaft 37 relative to the depth of screw socket 38 is such that the shank will strike the bottom of the socket before the screw head 39 binds upon the wall 35. Thus the screw head forms a guide at the lower surface of the wall 35 enabling the block 22 to slide freely in the trough-like support.

As the rod 27 is coupled by pivot 28 to the block 22, the rod 27 will be pulled to the left with the hook 23 and will therefore cause compression of the spring 31. The spring 31 therefore determines the amount of the angular movement by which the foot 18 will carry the hook 23 in the support 35. The spring 31 also cushions the impact. When the foot 18 has moved so far around to the left as to slip off the end of the flat spring 19, such spring 19 will snap back upwardly to its original position (Figure 1). The weight 17 will return the rod 16 back against the free end of the spring 19. The hook 23, being heavier than trigger 24, is now free to fall back to its original position where it is out of the path of the foot 18 and will not interfere with the next actuation of the device. The sampler is now set for the next cycle.

The launder 52 is constantly spilling its pulp in the launder 51. The operation of the drive, through the shaft 13, bevel pinions 42, 43 and shaft 44, causes the wedge-shaped cutter to revolve swiftly through the entire stream. After each revolution the cutter comes back to the position shown by solid lines in Figure 1. The sample cut out of the stream runs into the hollow shaft section 44^a and then into the sample bucket 50. The principal advantage of the improved sampler is that the cutter cuts the stream so rapidly that a small amount of sample is taken at each revolution, which in most cases will make it unnecessary to use riffle cutters in the launder to cut out a portion of the stream to be sampled.

The riffle cutters are objectionable, as, ordinarily installed, since they only cut out vertical slices of the pulp in the launder and the slots choke with wood pulp or material thrown into the launder, and they do not cut out a representative sample.

The drive can operate other types of samplers or machines requiring one quick revolution of shaft 13 either directly or by means of various transmission parts, such as worm or spur gearing.

It will be noted from Figure 1 that the centers of mass and gravity of the bucket 10 are to the lead side of bracket arm 12 referred to the direction of clockwise rotation; and the bucket arm 12 is normally in a vertical position. Also the weight arm 16 is not on the same diameter with bucket arm 12 but is offset from the diametric position by an angle which places the weight past its upper vertical position to the right when the bucket is at its lowest point, thus in-

suring the continued rapid rotation of the drive mechanism.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a movable sample cutter, a shaft coupled to drive said sample cutter, rigid arms fixed to said shaft at greater than 90° but less than 180° apart, a correlative water bucket and weight couple mounted for revolution in unstable equilibrium, said water bucket affixed to one arm, said weight affixed to the other arm, means to supply the bucket with liquid, a deformable resilient member against which the weight is adapted to rest in normal position, a foot carried around with the weight in a path intersecting the normal position of said member for depressing the member out of the path of the revolving weight, a weight check normally biased to inoperative position and movable into the path of said foot, and means for so moving said check and constructed and arranged for cooperating with said member to be operated by the member when deformed.

2. The combination of claim 1 in which said weight check device comprises a stop normally biased to a position out of the path of movement of said foot, said means being positioned to be actuated by said resilient member to overcome such bias and shift the stop into said path, and resilient means for cushioning the movement of said stop.

3. The combination of claim 1 in which said weight check comprises a movable stop normally biased to a position out of the path of movement of said foot and said means comprising a trigger arranged to be moved by said deformable resilient member to shift the stop into the path of the foot.

4. The combination of claim 1 in which said check comprises a rocker having a hook and said means comprising a trigger connected to the hook and positioned to be moved by the deformable resilient member to shift the hook into the path of the foot.

5. The combination of claim 1 in which said check comprises a pivoted stop member and said means comprising a tail-piece, with the stop member weighted to seek a normal position out of the path of movement of the foot, said deformable resilient member being normally in the path of movement of the foot and moved thereby out of such path, and positioned to shift the tail-piece and thereby the stop member into the path of movement of the foot.

6. The combination of claim 1, further characterized by the fact that the weight check is carried by a support capable of movement in the direction of movement of the weight and foot, and resilient restraining means coupled to said support.

7. The combination of claim 1 in which said weight check device comprises a movable support, resilient restraining means coupled to said

movable support, stop means on the support biased to an inoperative position out of the path of movement of said foot and said first-named means comprising a tail-piece positioned to be engaged by said deformable resilient member whereby to shift said stop means into said path of movement.

8. The combination of claim 1 further comprising means to initially hold the arms with the bucket positioned beneath the liquid supply means.

9. The combination of claim 1 in which the bucket is eccentrically carried by the bucket carrying arm with the center of mass of the bucket offset to the leading side of the bucket referred to its direction of rotation.

10. In combination with one launder spilling its contents into another launder, a sample cutter, a rotary shaft carrying the sample cutter, a drive shaft geared to said first shaft, rigid arms connected to said drive shaft at greater than 90° but less than 180° apart, a correlative water bucket and weight couple mounted for revolution in unstable equilibrium, said bucket carried by one arm with its center of gravity offset to the lead side of the direction of bucket revolution, said weight carried by the other arm, means to support the weight in a position offset from the vertical line to the bucket toward the lead side of the direction of weight revolution, and means to arrest the revolution after one turn.

11. In combination with one launder spilling its contents into another launder, a movable sample cutter, a shaft coupled to drive said sample cutter, rigid arms fixed to said shaft at greater than 90° but less than 180° apart, a correlative water bucket and weight couple mounted for revolution in unstable equilibrium, said bucket carried by one arm, said weight carried by the other arm means to supply the bucket with liquid, a deformable resilient member against which the weight is adapted to rest in normal position, a foot carried around with the weight in a path intersecting the normal position of said member for depressing the member out of the path of the revolving weight, and a check device comprising a stop normally biased to a position out of the path of movement of the foot, and means for moving the stop into such path of movement.

12. The combination of claim 11, wherein the bucket is open-topped with a hood over the leading side of the top to avoid premature dumping in the revolution of the bucket.

VINCENT C. LORENZ.
